(57) **CLAIM**

The ornamental design for a coffee tamper set with interchangeable tamper bases, as shown and described.

DESCRIPTION

FIG. 1 is a bottom perspective view showing an assembled state with a first tamper base of a coffee tamper set with interchangeable tamper bases;

FIG. 2 is a bottom perspective view showing an assembled state with a second tamper base of the coffee tamper set with interchangeable tamper base.

FIG. 3 is a bottom perspective view showing an assembled state with a third tamper base of the coffee tamper set with interchangeable tamper bases.

FIG. 4 is a top perspective view showing a detached state with the first, second and third tamper base of the coffee tamper set with interchangeable tamper bases.

FIG. 5 is a bottom perspective view thereof.

FIG. 6 is a front elevation view thereof, the rear, left, and right view being a mirror image thereof.

FIG. 7 is a top plan view thereof.

FIG. 8 is a bottom plan view thereof.

FIG. 9 is an enlarged view of detail 9 in FIG. 1; and, FIG. 10 is an enlarged view of detail 10 in FIG. 2.

The broken lines depict portions of the coffee tamper set with interchangeable tamper bases that form no part of the claimed design. The dot-dash broken lines in FIG. 1, FIG. 2, FIG. 9 and FIG. 10 depict the boundaries of the enlargements that form no part of the claimed design.
